U. S. PATENT OFFICE.

No. 66.

1861.

WHOLE No. 1,431.

Cooking Stoves.

N. S. VEDDER, OF TROY, N. Y.,
ASSIGNOR TO VINCENT, TIBBALS, SHIRK & CO., OF ERIE, PA.

Letters Patent for a Design, No. 66, dated May 28, 1861.

SPECIFICATION.

TO ALL WHOM IT MAY CONCERN:

Be it known, that I, N. S. VEDDER, of the city of Troy, in the county of Rensselaer, and State of New York, have invented or produced a new and original design for Cooking Stoves; and I do hereby declare the following is a full and exact description of the same, reference being had to the annexed photographic drawings, which make a part of this specification, and in which—

Fig. 1 is a perspective view of the whole stove, and

Fig. 2, of one of its feet on a larger scale.

My ornamental design for cooking stoves consists of the arrangement upon each foot A, shaped as shown by fig. 2, of two oak leaves b b, the acorn c, the two acorn cups d d, and the two scrolls e e, on the top plate F, made wider over the fire-box than over the oven, the rounded hanging edge g, on the upper front plate the raised words "Forest Oak," and the moulding h along and over the top and sides of the space for the doors I I, the moulding j on the edge of the hearth plate, the panel moulding k and oak leaves l l on the lower front plate, the compound moulding m along the base of the stove, the oak leaves n back of the projecting part o of the side plate, the compound moulding p along the border, and the oak leaf q, or oak leaves r r, on the middle of the doors S T U and I I respectively, the whole being shaped and disposed in combination, as shown by the annexed photographs.

Now, I do not claim as new any of the above mentioned ornamental parts separately, or independently of all the others, combined and arranged as above specified, and shown by the annexed photographic drawings.

Vedder's Design for Cooking Stoves.

What I claim as new and of my invention or production, and desire to secure by Letters Patent, is—

The above specified combination and arrangement of forms and mouldings, constituting the whole design of a cooking stove, as represented by the annexed photographic drawings, marked figs. 1 and 2.

Witnesses:

THOS. J. CORNELIUS,
AUSTIN F. PARK.

N. S. VEDDER.
